UNITED STATES PATENT OFFICE.

CHARLES F. ROGGENBAUCH, OF NEW YORK, N. Y.

TYPE-WRITING MACHINE.

SPECIFICATION forming part of Letters Patent No. 593,031, dated November 2, 1897.

Application filed February 27, 1897. Serial No. 625,280. (No model.)

To all whom it may concern:

Be it known that I, CHARLES F. ROGGENBAUCH, a citizen of the United States, residing in the city, county, and State of New York, 5 have invented certain new and useful Improvements in Type-Writing Machines, of which the following is a specification.

This invention relates to that class of type-writing machines in which the writing is visible and in which each type-bar is provided with two types for large and small letters, respectively, or for different characters.

The main object of the invention is to impart a vertical oscillatory movement to the 15 platen and at the same time to so relatively arrange the faces of the types or characters as that their planes will be at right angles to the radii of the platen in the two positions of the same, so that the impact of each type or character will be directly toward the axis of the 20 platen, whereby in that class of type-writing machines where the platen moves in a curve the printing which is produced will always be perfect, as the type or character will always 25 strike the surface of the platen squarely.

A further object of the invention is to simplify and render more efficient the means for returning the type-bars to normal position after the same have been actuated by the key-levers, and also to simplify the intermediate 30 connections between the returning medium, the type-bars, and the key-levers.

The invention also has for its object to reconstruct and generally rearrange the construction of type-writing machines so as to both simplify the same and render them more easy of manufacture.

In the accompanying drawings, Figure 1 is a 40 plan view of a type-writing machine embodying my improvements, some of the key-levers and the related parts, however, only being shown, as the others are substantially duplicates. Fig. 2 is a longitudinal vertical section of the machine on line 2 2, Fig. 1. Fig. 45 3 is a front elevation, partly in section, on line 3 3, Fig. 1. Fig. 4 is a broken detail sectional view showing the manner of constructing the operating or knuckle joints between the key-levers, type-bars, and type-bar-returning 50 slides. Fig. 5 is a similar view showing a different position of the same parts when the key-lever has been depressed so that the type-

bar is raised into vertical position and the returning-slides of the type-bars acted on, said figure also showing in dotted lines the platen in lower position; and Fig. 6 is a broken detail view showing more particularly the guide-rail for the wheel of the carriage of the platen, and also showing the outermost type or character of a type-bar as having struck the platen, 60 which latter is shown in raised position.

Similar letters of reference indicate corresponding parts.

Referring to the drawings, A indicates the base-board, A' the base-plate of the machine, 65 which is placed upon and connected with the base-board in any approved manner, and A² represent uprights arranged at the rear part of the base or bed plate of the machine, which are connected by and carry at their upper 70 ends the segmental plate B, the curved portion of which hangs downwardly. The type-bars are hung in any approved manner upon this segmental plate, to be hereinafter fully described.

To the rear of the bed or base plate A' of the machine are uprights A³, which are connected by a horizontal cross-rod A⁴. To this cross-rod are pivoted two swinging arms D, which carry at their outer ends on a suitable 80 axis or journal-bearings the usual platen C, over which the paper is caused to pass, so as to receive the impression of the type or characters of the type-bar mechanism. These swinging arms D constitute a portion of the 85 carriage which traverses the machine cross-wise, while the other portion of the carriage consists of a U-shaped frame D', which is pivoted at d to the ends of the arms D forwardly of the journals or shaft C' of the platen and 90 which is provided at about its mid-length with a grooved supporting wheel or roller d', that runs upon a suitable guide-rail e of a vertically-movable frame E. Inasmuch as the frame E moves in a vertical path the roller 95 d' is supported on the pivoted frame D', whereby the roller is always permitted to ride truly and correctly on the guide-rail e.

The frame E is separated a suitable distance from the uprights A² and the segmental plate 100 B, so that a hook d², fixed to the U-shaped frame D' of the carriage, can extend through the space and engage under the top rail e of said vertically-movable frame D'. To set

this vertically-movable frame off from the segmental plate B a suitable distance and also to furnish guides for the same, there are secured to the upper end of each of the uprights 5 A² angular brackets *a*, which are grooved on their inwardly-presented faces, as shown at *a'*, so as to receive the tongues or projections *d*³, extending from the ends of the top rail *e* of said frame E.

10 The frame E is moved upwardly, so as to swing the platen on the arm D of the carriage, by means of a lever F, which is pivotally connected at its inner end to one of the side bars of the frame E, is fulcrumed intermediately of 15 its ends on a cross-rod G, supported in brackets *g* of the bed-plate of the machine, and is furnished at its outer end with a key *f*. By depressing the key of the lever F the frame E is raised, with the result that the U-shaped 20 frame B' of the carriage is also raised, while consequently the arms D are oscillated and raised, thus raising the platen C, the axis of which describes a slight curve forming the circumference of a circle, of which the cross- 25 rod A⁴ is the center.

Inasmuch as the reciprocating movement of the frame E has to be transferred into an oscillating movement in the arms D the U-shaped frame D' of the carriage must be pivoted, as shown at *d*, to said arms D, so that said U-shaped frame D' has a slight backward-and-forward play; but this, while it at the same time causes the supporting-wheel of the carriage to slowly oscillate in its own 35 plane, is compensated for by furnishing the top guide-rail *e* of the reciprocating frame E with a raised bead or flange *e'*, on which the wheel can rock. The carriage can be caused to travel back and forth by any approved 40 mechanism, which is not necessary to be herein shown, and of course any well-known ribbon mechanism can also be used.

The mechanism for actuating the type-bars will now be described. The type-bars H are 45 hung in transverse slots *b* in a curved flange B', which is arranged on the lower curved edge of the segmental plate B. *h*² is the supporting-wire which extends across said slots *b*. The inner end or heel ends of the type- 50 bars H are enlarged, so as to provide laterally-extending wings *h*, which are provided with slots *h'*, that extend in the direction of the length of the shanks or stems of the type-bars, so as to open in the direction of the 55 types or characters, while the inner ends of the slots *h'* are laterally offset at *h*². By thus slotting the wings *h* of the type-bars the same can be readily assembled in the machine and can also be readily removed for the purpose 60 of renewing a broken or damaged type-bar, while at the same time the offsetting of the slots at *h*² furnishes a suitable means whereby the type-bars are prevented from being displaced accidentally, as the fulcruming-wire 65 *b*⁰ receives such offset portions of the slots. To detach a type-bar, it is necessary to slightly raise the inner end of the same and then push

the type-bar rearwardly. The type-bars for the purpose of their actuation are further provided with laterally-projecting pins *h*³, 70 extending from the wings *h*, and adjacent to and in advance of said pins *h*³ the type-bars are provided with rearwardly-presented shoulders *h*⁴. The shoulder *h*⁴ is engaged by a laterally-projecting pin *i* at the upper end 75 of each of the L-shaped key-levers I, while the pin *h*³ on the type-bar is engaged by a finger *i'*, extending upwardly from the short arm of each of the L-shaped key-levers and arranged to the rear of the pin *i* thereon. 80 The key-levers are, at the elbows of the same, furnished with open recesses *i*², which receive the cross-rod J, whereby the key-levers are fulcrumed to the machine, said cross-rod J being supported in suitable brackets fixed to 85 the base or bed plate A'. The key-levers I are provided at their outer ends with the customary keys *i*³ and are held in proper horizontal position by means of a stop-rod *l*, which is fixed to a frame L, supported on the base 90 or bed plate A'. The type-bars when in normal position are supported and rest upon a semicircular cross-bar *l'* of said upright frame L. The brackets for supporting the cross-rod J, on which the key-levers I are fulcrumed, 95 are preferably formed from a single casting or block *j*, which extends transversely of the bed or base plate and which is furnished with slots *j'*, into which the elbows of the key-levers extend. 100

The short arms of the key-levers are furnished with longitudinal slots *k*, parallel with which is fixed in each key-lever a flat spring *k'*, the object of which is to hold the hooked end of a tension-spring K in engagement with a series of notches *k*², formed in one of the walls of the slot *k*. Said hooked ends of the tension-springs K can be adjusted into any one of the notches *k*², so as to increase or decrease the tension of the spring and thereby 110 either cause the key-levers to return directly or slide to normal position, while this adjustment of the spring is further effectuated by means of notched studs *k*⁰, which project from a ledge extending rearwardly from the 115 cross-block *j*, on which the key-levers are fulcrumed. 120

It will be observed that there is no positive pivotal connection of the key-levers with the machine nor with the type-bars, nor is there 125 a positive connection of the latter with the machine. This is done for the purpose of facilitating the assembling of the parts, and also to render it easier to repair the machine in case of breakage of some of these parts. 130

In depressing one of the key-levers I the pin *i*, which is normally in contact with the shoulder *h*⁴ of the actuated type-bar, is caused to first impart to the type-bar an upward-swinging movement, which movement is taken up and completed by a second or continued impulse to the type-bar by the finger *i'* of the key-lever, which is forced against the lateral pin *h*³ on the type-bar, the two but 135

continuous actuations of the type-bar imparted by the coöperation of the pin i , shoulder h^4 , finger i' , and pin h^3 , thus completing the upward swinging of the type-bar to vertical position, so that one of the types or characters $o o'$ is brought against the paper on the platen C. This construction of the joints between the key-levers and the type-bars also enables an easy movement of the parts.

The types or characters $o o'$ are arranged in pairs on the outer ends of each type-bar H in the well-known manner, one of the same being a capital and the other a small letter, but the disposition of the printing-faces of these types or characters is different than heretofore, inasmuch as the same are inclined so as to have an upward or outward slant away from a point intermediately of the two types or characters. In other words, the printing-faces are inclined inwardly toward each other. This disposition of the printing-faces of the types or characters is necessitated by reason of the fact that the platen C, in being oscillated up and down, is caused to describe a curve, and if the printing-faces of the types or characters were not inclined, as in this case, although one of the same would strike the platen squarely the other would not.

The type-bars are returned to their normal position by the following mechanism: M indicates a swinging returning-frame, which is fulcrumed at its lower ends to a suitable cross-rod m and is under a forward stress imparted to the same by means of a flat spring N, which is in engagement with a rearwardly-projecting heel m' , extending from the central bar of said frame M. The upper or top cross-bar M' of the frame M is semicircular or arc-shaped and engages with a series of semicircularly-arranged type-bar-returning slides P, which at their rear ends are guided in openings in a semicircular or curved guide-plate Q, which is supported from the brackets a. The forward portions of the type-bar-returning slides P enter side extension-slots b^x of the slots b , which are formed in the segmental plate B. The extreme forward ends of the type-bar-returning slides P are each formed with two lobes $r r'$, which form between them a rounded cavity. Above or in front of the slot h' in the heel-wing h of each type-bar H are formed two cavities or depressions $h^5 h^6$, between which the same is thereby provided with a nose h^7 , having a convex contour. In normal position of the type-bars the lowermost lobes r' of the type-bar-returning slides rest against the noses h^7 of the type-bars, while when the type-bars are forced upwardly into vertical position by the key-levers the noses act upon said lowermost lobes, so as to force the returning-slides rearwardly against the returning-frame M. The rearward movement of each type-bar-returning slide P is not completed entirely by the impact of the nose h^6 against the lowermost

lobe of the type-bar-returning slide, but is completed and taken up by the recessed portion h^5 of the type-bar coming against the upper lobe r of the type-bar-returning slide. In this manner the type-bars when moving in an angle of ninety degrees are caused to project the type-bar-returning slides rearwardly to their fullest extent without straining any part of the mechanism, while the return of the type-bars to normal position is accomplished by the forwardly-actuated type-bar-returning slides in a similar manner without straining any of the mechanism.

All the parts of my improved type-writing machine, especially the key-lever and type-bar mechanism, are easily assembled in the machine, are smoothly operated, and are readily taken apart without endangering the practicability and effectiveness of the machine.

Having thus described my invention, I claim as new and desire to secure by Letters Patent—

1. In a type-writing machine, the combination of a frame, a carriage, a platen on the carriage, a series of type-bars, each carrying a pair of types or characters, the printing-faces of the types or characters being inclined inwardly toward each other, key-levers, and means for imparting an oscillatory movement to the platen, substantially as set forth.

2. In a type-writing machine, the combination of a frame, a carriage, a platen journaled in the carriage provided with a laterally-oscillating roller, a vertically-movable frame provided with a top rail, means for guiding said movable frame, said carriage being guided and suitably supported on said top rail, a vertical plate in front of said movable frame and forming a part of the frame of the machine, a series of type-bars pivoted to said vertical plate, and each carrying a pair of types, key-levers, and means for imparting a vertical oscillating movement to the carriage and platen through the medium of said movable frame, substantially as set forth.

3. In a type-writing machine, the combination, with an oscillatory platen, and means for oscillating said platen, of a series of type-bars, and means for actuating the same, said type-bars being provided with a pair of types or characters, which are inclined relatively with respect to each other, substantially as set forth.

4. In a type-writing machine, the combination, with the segmental supporting-plate provided with means of support for the type-bars, of the type-bars fulcrumed to said support and provided with shoulders and lateral pins, and the key-levers provided with pins extending in opposite direction to the pins on the type-bars for engaging the shoulders on the latter, and with upwardly-extending fingers arranged to the rear of their pins for engaging the pins on the type-bars, substantially as set forth.

5. In a type-writing machine, the combina-

tion, with the type-bars, and key-levers for actuating the same, of tension-springs, the ends of which are adapted to take into a series of notches in the short arms of the key-levers, and flat springs for holding said tension-springs in position, substantially as set forth.

6. In a type-writing machine, the combination, with the type-bars, and the key-levers for actuating the same, said type-bars being provided with two cavities and a nose between the cavities, of the type-bar-returning slides guided in a part of the frame of the machine, and provided with two lobes engaging in the cavities of the type-bars, a guide for supporting said slides, and a spring-actuated device for returning the slides and the type-bars to normal position, substantially as set forth.

15

7. The combination, with the key-levers, 20 and the type-bars actuated by said levers, of a series of semicircularly-arranged type-bar-returning slides, normally engaging the type-bars, means for guiding the said slides, and a rocking and spring-actuated device provided at its upper part with an arc-shaped or semicircular portion engaging the rear ends of the semicircularly-arranged series of type-bar-returning slides, substantially as set forth.

25

In testimony that I claim the foregoing as my invention I have signed my name in presence of two subscribing witnesses.

CHARLES F. ROGGENBAUCH.
